TUNABLE MAGNETRONS

Chester C. Amsden, Lexington, and Carlton G. Lehr, Waltham, Mass., assignors to Raytheon Manufacturing Company, Waltham, Mass., a corporation of Delaware

Application October 22, 1954, Serial No. 464,229

5 Claims. (Cl. 315—39.61)

This invention relates to electron discharge devices, and, in particular, to microwave magnetron discharge devices having variable tuning structures.

It has been found desirable for certain purposes to be able to mechanically tune or change the output frequency of electron discharge devices of the magnetron type, while such devices are in operation. Structures have previously been devised for the accomplishment of such results by the use of a diaphragm structure between the movable tuner section and the stationary member of the magnetron. In such structures a tuning member is mechanically movable with respect to the resonant cavities of the magnetron. In order to maintain a hermetic seal inside the envelope and at the same time permit movement or adjustment of the tuning member, a flexible diaphragm is sealed to the inner wall of the stationary structure and also sealed around the movable tuning member. It is essential that the heat which is developed by circulating R. F. currents in the tuning member of the magnetron be conducted away. If this heat is not removed, the temperature of the tuner will rise until gas detrimental to the operation of the tube is emitted and in some cases melt the tuner. The difficulty in conducting heat away from the tuner arises from the fact that the tuner is in a vacuum and is movable. Cooling is usually accomplished by passing a liquid against the diaphragm section exposed to atmospheric pressure, thereby conducting the heat away.

The diaphragm type of construction is very satisfactory in applications where the frequency of the magnetron is varied infrequently and the total mechanical linear distance that the tuner is moved is kept very small. Even in tubes having the LC type of tuners, which is recognized by those skilled in the art as giving the greatest frequency variation for the smallest linear change of the tuner, the total linear change of the tuner necessary to give the frequency variations capable of being produced by the modern magnetrons will cause the diaphragm to break due to fatigue long before the normal tube life has expired. A later improvement on this type of tube has been to substitute a bellows type of construction for the diaphragm. The action of the bellows is very similar to the action of the diaphragm with the added advantage that greater linear movement of the tuner can be had. The bellows is cooled by a coolant in a similar manner as the diaphragm is cooled by circulating the coolant on that side of the bellows open to the atmosphere. In both the diaphragm and bellows type of construction it is impossible to rapidly change the frequency of the magnetron by moving the tuner due to the heavy weight of tuner plus coolant and the large unbalance caused by the moving coolant.

It is an object of this invention, therefore, to devise a means for cooling the tuner of a tunable magnetron wherein the tuner is to be varied at a rapid rate over the frequency output range of the magnetron. Another object is to accomplish the aforesaid object in a cheap and

2

simple manner wherein the weight of the tuning member is not increased and the total movement of the tuning member is not limited by the cooling means.

The foregoing and other objects of the present invention will be best understood from the following description of an embodiment of the invention, reference being made to the accompanying drawings wherein:

Fig. 1 is a cross-sectional view of a tunable electron-discharge device illustrating an embodiment of the invention;

Fig. 2 is a detailed view of Fig. 1 illustrating the connection between the cooling members and the tuning structure;

Fig. 3 is a detailed view of Fig. 1 illustrating the connection between the cooling members and the anode structure;

Fig. 4 is a top view of an embodiment of a cooling device;

Fig. 5 is a section 5—5 of Fig. 4; and

Fig. 6 is a section 6—6 of Fig. 1.

Referring now to Figs. 1, 2, 3 and 6, there is shown an electron-discharge device of the magnetron tube type comprising an anode structure 10, a cathode structure 11, and magnetic means 12 for establishing a magnetic field 25 in the direction perpendicular to the path of electron flow between said cathode and anode structures. The anode structure 10 has a cylindrical hole 13 centrally located therein. Extending radially inward from the sides of said anode 10 is a plurality of anode vanes 14 which are positioned symmetrically about the axis of said hole 13. As illustrated, the anode vanes 14 are substantially rectangular members of conductive material, such as copper, which are rigidly secured to the anode structure 10 and which extend to a point somewhat short of the axis of hole 13. The lower edges of anode vanes 14 are alternately connected by conductive straps 15 to prevent operation of the device in spurious modes. The lower end of hole 13 is covered by an end plate 16, which is attached to anode structure 10. Positioned on plate 16 and extending through an aperture therein is a lower magnetic pole piece 17. Extending through an aperture in pole piece 17 is the cathode structure 11 which is cylindrical in form, and is positioned axially in hole 13. The cathode structure 11 comprises a support cylinder 18 coated with electron emissive material at the point where said cylinder passes between the ends of anode vanes 14. The upper end of cylinder 18 is connected to a conductive hat 19, the edges of which extend out beyond the electron emissive material coat on cylinder 18. A cylinder 20 surrounds and engages the cathode cylinder 18 below the electron emissive portion. Cylinder 20 in cooperation with hat 19 substantially prevents movement of electrons from the cathode structure 11 in a direction axially of the hole 13. Cylinder 20 extends through the aperture in lower pole piece 17 and is spaced therefrom. Cylinder 20 is attached to a lower support member 21, which is connected through a glass support seal 22, coaxial with support member 21 through a metallic cylinder 23 which, in turn, is rigidly connected to lower pole piece 17. Support member 21, part of which is hollow, contains a conductor therein which is insulated and supported by ceramic seal 24. Said inner conductor is connected to one end of a cathode heater 25, which is positioned inside the cathode cylinder 18 adjacent the electron emissive coating. The other end of said heater 25 is connected to the end hat 19. The details of the cathode structure are illustrated and described herein by way of example only, it being understood that any desired cathode structure may be used.

Extending downward into the cavity formed by the anode vanes 14 is a plurality of tuner elements 26 which

is supported by the body of a tuner structure 27. The tuner structure 27 comprises an upper ring 28 to which the tuner elements 26 are attached. The tuner structure 27 is rigidly attached to a movable magnetic pole piece 29, which is shown in the fully retracted position. The pole piece 29 is free to slide within the magnetic cylindrical structure 30 to which the magnetic means 12 is attached. The magnetic pole piece 29 is capable of being moved along the axis of hole 13. A vacuum seal is maintained between the magnetic pole piece 29 and the outside atmosphere by means of a bellows arrangement 31. The bellows 31 is sealed at the pole piece 29 and also at the upper end of moving means 32, which consists of a threaded shaft 33 and a knob 34. It is clearly understood that the type of bellows arrangement and tuner support structure may be of any desired type.

In order to cool the tuning structure 27, two flexible cooling members 35 of good conducting material are rigidly connected between pole piece 29 and anode structure 10. The heat generated in the tuning structure 27 is conducted through the cooling members 35 and thence into the anode block which acts as a heat sink. The cooling members 35 are constructed in the form of a spider having eight legs 36, as shown in Figs. 4 and 5. The periphery of legs 36 are rigidly connected to anode 10, as shown in Fig. 3, while the central opening 37 is connected to the movable pole piece 29, as shown in Fig. 2. The legs 36 are constructed in the form of a U in order to allow the greatest possible movement of the tuning structure 27. The specific embodiment of the cooling structure illustrated in Figs. 4 and 5 is shown in a complete electron discharge device illustrated in Fig. 1. In order to provide sufficient cooling means and also have great strength over repeated cyclings of the moving means 32, two cooling members 38 and 39 have been used. Each cooling member 38 and 39 has been constructed of unannealed copper having a thickness preferably no greater than 0.005 of an inch. This particular type of construction allows the moving means 32 of the tuning structure 27 to be cycled very rapidly without causing failure of the cooling members 38 and 39 due to fatigue.

Fig. 2 shows a detailed view of how cooling members 38 and 39 are connected to pole piece 29. Good heat transfer between the pole piece 29, the tuner element 26, and the cooling members 38 and 39 is achieved by using five washers 40 constructed of good conducting material, one washer placed on each external side of each cooling member and three washers placed intermediate the cooling members. The cooling members 38 and 39 and the five washers 40 are silver soldered to each other and to the pole piece 29 and ring 28. Fig. 3 is a detailed view illustrating how cooling members 38 and 39 are rigidly connected to the anode block 10. Good heat transfer is assured from the cooling members 38 and 39 into the anode block 10 by means of five washers 41 constructed of good conducting material, one placed on each external side of the cooling members and three washers placed intermediate the cooling members. The cooling members 38 and 39 and the five washers 41 are silver soldered to each other and to the anode block 10.

A signal output structure 42 is provided comprising a pick-up loop 43 extending into one of the cavities between the anode vanes 14. One end of loop 43 is connected to the anode block 10 and the other end of loop 43 extends out through a hole in the anode block 10 to form the central conductor 44 of a coaxial line. A vacuum seal is provided between the central conductor 44 and an outer conductor 45 of said line which is sealed in the anode block 10.

When a suitable heater voltage is applied to the anode heater, by means of a heater voltage supply 46, and a suitable high voltage is applied between the cathode and anode by means of a high voltage supply 47, the device will oscillate at a frequency determined by the dimen-

sions of the cavities formed between anode vanes 14 and the relative position of the tuner elements 26 as determined by the position of the tuner structure 27. The tuner elements 26 are shunted together by means of a conductive strap 48 to prevent spurious oscillations. The particular elements illustrated herein are constructed to form what is called an LC tuner. This type of tuner is recognized as giving the greatest frequency variation for a given linear displacement of the tuning vanes in a resonant cavity. However, any other desired type of tuning may be used such as, for example, slug or, inductance tuning, or as is used here, a combination of inductance and capacitance tuning.

This completes the description of the particular embodiments of the invention illustrated herein. However, many modifications thereof will be apparent to persons skilled in the art without departing from the spirit and scope of this invention. For example, any desired magnetron anode configuration may be used. The tuner structure is not necessarily limited to the cavity structure illustrated herein. There may be one or many cooling members, each cooling member having a plurality of legs consistent with good engineering practices. The shape of the cooling members is not necessarily limited to a U form but may be constructed of any shape depending only on the total movement of the tuning structure used and the amount of heat to be dissipated. Accordingly, it is desired that this invention be not limited by the particular details described herein, except as defined by the appended claims.

What is claimed is:

1. An electron discharge device comprising a cathode, an anode structure spaced from said cathode, said anode structure defining a cavity resonator having a plurality of cavities, a tuning structure comprising a plurality of tuning elements movably positioned with respect to said cavity resonator, means adjacent said anode structure for producing a magnetic field in the space between said cathode and said anode, means for moving said tuning element of said tuning structure into and out of said anode resonator, a movable sealing means for sealing the tuning structure, and a separate means for cooling said tuning structure.

2. An electron discharge device comprising a cathode, an anode structure spaced from said cathode, said anode structure defining a cavity resonator having a plurality of cavities, a tuning structure comprising a plurality of tuning elements movably positioned with respect to said cavity resonator, a member of magnetic material positioned adjacent said cavity resonator and movable with respect thereto, means for moving said tuning element of said tuning structure into and out of said anode resonator, means for moving said magnetic material in the same manner as the tuning structure is moved, a bellows arrangement for sealing the tuning structure, and a separate means for cooling the tuning structure and said magnetic material member.

3. An electron discharge device comprising a cathode, an anode structure spaced from said cathode, said anode structure defining a cavity resonator having a plurality of cavities, a tuning structure comprising a plurality of tuning elements movably positioned with respect to said cavity resonator, means adjacent said anode structure for producing a magnetic field in the space between said cathode and said anode, means for moving said tuning element of said tuning structure into and out of said anode resonator, a movable sealing means for sealing the tuning structure, and a separate flexible conducting member connected between said tuning structure and said anode for cooling said tuning structure.

4. An electron discharge device comprising a cathode, an anode structure spaced from said cathode, said anode structure defining a cavity resonator having a plurality of cavities, a tuning structure comprising a plurality of tuning elements movably positioned with respect to said

cavity resonator, means adjacent said anode structure for producing a magnetic field in the space between said cathode and said anode, means for moving said tuning element of said tuning structure into and out of said anode resonator, a movable sealing means for sealing the tuning structure, and a separate conducting member having both a central opening wherein the tuning structure is connected and a plurality of legs having a U-shaped form for flexibility which are fastened to the anode for cooling said tuning structure.

5. An electron discharge device comprising a cathode, an anode structure spaced from said cathode, said anode structure defining a cavity resonator having a plurality of cavities, a tuning structure comprising a plurality of tuning elements movably positioned with respect to said

15

cavity resonator, a member of magnetic material positioned adjacent said cavity resonator and movable with respect thereto, means for moving said tuning element of said tuning structure into and out of said anode resonator, means for moving said magnetic material in the same manner as the tuning structure is moved, a bellows arrangement for sealing the tuning structure, and a separate conducting member having both a central opening wherein the tuning structure is connected to the magnetic material and a plurality of legs having a U-shaped form for flexibility which are fastened to the anode for cooling said tuning structure and said magnetic material.
